UNITED STATES PATENT OFFICE.

CHARLES M. MINTON, OF PHILOMATH, OREGON.

SAW-HANDLE.

981,100.

Specification of Letters Patent. Patented Jan. 10, 1911.

Application filed April 2, 1910. Serial No. 553,037.

To all whom it may concern:

Be it known that I, CHARLES M. MINTON, citizen of the United States, residing at Philomath, in the county of Benton and State of Oregon, have invented certain new and useful Improvements in Saw-Handles, of which the following is a specification.

This invention relates to saw handles and has for its object to effect certain improvements in this class of devices, whereby the handle may be readily attached to or detached from a saw.

A further object of the invention is to provide a handle, capable of being adjusted at any angle or inclination with respect to the longitudinal plane of the saw, thereby to facilitate the sawing of logs and the like.

A further object is to provide a saw with relatively stationary and movable handle sections, one of which is provided with a locking pawl adapted to engage a toothed sleeve carried by the socket of the mating handle section, thereby to lock the saw in different positions of angular adjustment.

A still further object of the invention is generally to improve this class of devices, so as to increase their utility, durability and efficiency.

Further objects and advantages will appear in the following description, it being understood that various changes in form, proportions and minor details of construction may be resorted to within the scope of the appended claims.

For a full understanding of the invention and the merits thereof, reference is to be had to the following description and accompanying drawings, in which:

Figure 1 is a perspective view of a saw handle constructed in accordance with my invention; Fig. 2 is a vertical sectional view of the same partly in elevation; Fig. 3 is a vertical sectional view taken on the line 3—3 of Fig. 2; Fig. 4 is a transverse sectional view taken on the line 4—4 of Fig. 2; Fig. 5 is a detail perspective view of the locking pawl detached.

Corresponding and like parts are referred to in the following description and indicated in all the views of the drawings by the same reference characters.

The device comprises a casing or housing 5 having a transverse bore 6 and provided

with oppositely disposed sockets 7 and 8, one of which receives a relatively stationary handle section 9, the exterior walls of the other socket 8 being threaded for engagement with a relatively movable handle section 10.

Extending laterally from one side of the casing 5 and preferably formed integral therewith is a tubular extension 11, the interior walls of which are preferably disposed in horizontal alinement with the bore 6 so as to form a continuation of the latter.

Mounted for rotation in the extension 11 is a tubular member or sleeve 12 having one end thereof extended within the bore 6 and provided with a circumferential row of ratchet teeth 13 and its opposite end threaded exteriorly at 14 for engagement with the interiorly threaded walls of a nipple 15 carried by a saw guard or shield 16. The guard or shield 16 is provided with a longitudinally disposed seating groove 17 for the reception of the adjacent end of the saw, indicated at 18, the lower end of the guard 16 being bent laterally to produce an arm 19 adapted to form a housing for the teeth of the saw and thus prevent the latter from coming in contact with and cutting or otherwise lacerating the hand of the operator.

Housed within the tubular member or sleeve 12 is a clamping device, preferably in the form of a bolt 20 having its head 21 bearing against a shoulder 22 formed in the bore 6 and its reduced end bifurcated to form an intermediate slot for the reception of the saw 18, there being transversely alined openings formed in the bifurcated end of the bolt 20 to permit the insertion of a fastening device or pin 23, which latter extends through a corresponding opening in the bottom of the saw, as shown.

A washer 24 is interposed between the head 21 of the bolt and the adjacent end of the tubular member 12, said washer being formed of yieldable material so as to prevent injury to the parts when the latter is adjusted to clamp the saw in position on the guard 16.

An opening 25 is formed in the socket member or casing 5 opposite the head of the bolt 20, the walls of said opening being threaded for engagement with a correspondingly threaded plug or closure 26. The in-

ner face of the plug 26 is preferably concaved to form a seat for the head of said bolt 20, while the outer face thereof is provided with a transverse kerf or key seat 27, 5 so that by introducing a screw driver or other tool in said seat 27 and rotating the plug 26, the latter may be removed, thus to permit the insertion or removal of the clamping bolt 20.

- 10 The free end of the arm 19 is preferably flattened at 28 so that when the saw 18 is removed from the guard, the flattened portion 28 of the arm 19 may be inserted in the seat 27 of the plug for rotating the latter.
- 15 The movable handle section 10 is provided with a collar 29 having its interior walls threaded at 30 for engagement with the threads on the socket 8, said collar being provided with a transverse partition, or 20 diaphragm 31 which extends across the adjacent end of the handle section 10, and is provided with an opening 32.

Disposed within the socket member 8, is a locking pawl 33 having a reduced portion or 25 neck 34 which extends through the opening 32 and is upset at 35, there being a recess 36 formed in the adjacent end of the movable handle section 10 to permit rotation of the handle on the socket 8 to effect the clamping of the sleeve 12 without binding or 30 wedging action between the parts.

The lower end of the locking pawl 33 extends through a square opening 36 formed in the casing or housing 5 and is provided 35 with a concave face 37 having teeth or serrations formed thereon and corresponding in shape to and adapted to engage the teeth on the sleeve 12 for the purpose of holding the saw in different positions of angular adjustment. Thus it will be seen that by rotating 40 the movable handle section 10, the pawl 33 will be forced into engagement with the teeth on the sleeve 12 and thus lock the latter in engagement with the casing 5. By 45 now holding the guard 16 stationary and rotating both handles in a vertical plane, the tubular extension 11, together with the sleeve 12 may be adjusted rearwardly, thus causing the clamping member 20 to force the 50 saw 18 within its seat 17 and effectually prevent wobbling movement of the same during the sawing operation.

In order to detach the handle sections, it is merely necessary to rotate said handle sections in the opposite direction which moves 55 the fastening device or bolt 20 in the direction of the saw 18 and thus disengages the adjacent end of the saw from the seating groove 17 so that by removing the pin 23, 60 the saw blade may be readily detached.

When it is desired to adjust the handle at any angle or inclination with respect to the longitudinal plane of the saw, it is merely necessary to rotate the handle section 10 until 65 the pawl 33 is disengaged from the teeth

on the sleeve 12, thus permitting both handle sections to be rotated in a vertical plane until the desired adjustment is effected, the handle sections being locked in adjusted position by again rotating the movable handle section 10 until the active end of the pawl 33 engages the teeth on the sleeve 12. 70

The device is simple in construction and thoroughly practical in operation and will effectually hold the handle in different positions of adjustment with respect to the saw. 75

Having thus described the invention, what is claimed as new is:

1. A device of the class described including a casing having a tubular extension, a relatively stationary handle section secured to one end of the casing, a movable handle section mounted for rotation on the other end of the casing, a saw guard telescoping the tubular extension, a sleeve disposed within said extension and operatively connected with the saw guard, a fastening device extending through said sleeve and adapted to clamp the saw in engagement with the guard, and a locking member carried by the movable handle section and movable into engagement with the sleeve when said handle is rotated about its longitudinal axis. 85

2. A device of the class described including a casing, relatively stationary and movable handle sections carried by the casing, a saw guard, a sleeve mounted for rotation in the casing and engaging the guard, a fastening device extending through the sleeve for clamping the saw in engagement with the guard, and a locking pawl carried by the movable handle section and adapted to engage the sleeve when said movable handle section is rotated on the casing about its longitudinal axis. 90

3. A device of the class described including a casing having its exterior walls threaded at one end thereof, a relatively stationary handle section secured to one end of the casing, a movable handle section mounted for rotation on the threaded end of the casing, a saw guard slidably mounted in the casing, a sleeve having one end thereof provided with means for engagement with the saw guard and its other end provided with ratchet teeth, a fastening device extending through the sleeve for clamping the saw in engagement with the guard, and a locking pawl swiveled on the movable handle section and adapted to engage the teeth on the sleeve 100 when said movable handle section is rotated on the casing about its longitudinal axis. 105

4. A device of the class described including a casing provided with a transverse bore and having one end thereof threaded, a relatively stationary handle section secured to one end of the casing, a movable handle section having a threaded collar engaging the threaded end of the casing, a saw guard slidably mounted in the casing, a sleeve dis- 110

posed within the bore and having one end thereof threaded in the guard and its other end provided with ratchet teeth, a fastening device extending through the sleeve for 5 clamping the saw in engagement with the guard, a removable plug extending over the fastening device and forming a closure for one end of the bore, and a locking pawl carried by the movable handle section and 10 adapted to engage the teeth on the sleeve when the movable handle section is rotated about its longitudinal axis.

5. A device of the class described including a casing having a transverse bore, the 15 wall of which is provided with a shoulder, a relative stationary handle section secured to one end of the casing, a movable handle section mounted for rotation on the other end of the casing, a saw guard having 20 a sliding engagement with the casing, a sleeve disposed within the bore of the casing and having one end thereof provided with means for engagement with the guard and its other end provided with ratchet 25 teeth, a fastening device having one end thereof provided with a head bearing against the shoulder and its other end bifurcated and engaging the saw for clamping the latter on the guard, a removable plug 30 forming a closure for one end of the bore and provided with a concaved inner face for the reception of the head of the fastening device, and a locking pawl swiveled on the movable handle section and adapted to engage 35 the teeth on the sleeve when said handle section is rotated about its longitudinal axis.

6. A device of the class described including a casing having one end thereof threaded and its intermediate portion provided 40 with a tubular extension, there being a transverse bore formed in the casing and extension, respectively, a stationary handle section secured to one end of the casing, a movable handle section having a threaded collar engaging the threads on the casing and provided with a transverse partition, a saw guard having a nipple telescoping the tubular extension of the casing and provided 45 with interior threads, a sleeve having one end thereof threaded for engagement with the threads on the nipple and its other end provided with a circumferential row of ratchet teeth, a fastening device extending 50 through the sleeve for clamping the saw in engagement with the guard, and a locking pawl swiveled in the partition of the movable handle section and adapted to engage 55 the teeth on the sleeve when said movable handle section is rotated about its longitudinal axis.

7. A device of the class described including a casing having one end thereof threaded and its intermediate portion provided with 60 a tubular extension, there being a transverse

bore formed in the tubular extension and casing, respectively, and a square opening formed in said casing and communicating with the bore, a stationary handle section secured to one end of the casing, a movable 70 handle section provided with a threaded collar engaging the threaded end of said casing and provided with a transverse partition, a saw guard having a nipple slidably mounted in the tubular extension of the casing, a 75 sleeve having one end thereof provided with circumferential teeth and its other end operatively connected with the nipple of the guard, a fastening device extending through the sleeve for clamping the saw in engagement with the guard, a removable closure 80 forming a housing for one end of the fastening device, and a locking pawl swiveled in the partition of the movable handle section and having its active end extending through 85 the square opening in the casing for engagement with the teeth of the sleeve when said movable handle section is rotated.

8. A device of the class described including a casing having a tubular extension and 90 provided with a transverse bore, the wall of which is formed with a stop shoulder, a stationary handle section secured to one end of the casing, a movable handle section mounted for rotation on the other end of the 95 casing, a saw guard having an interiorly threaded nipple slidably mounted in the tubular extension, a sleeve having one end thereof provided with threads for engagement with the threads on the nipple and its 100 other end provided with ratchet teeth, a clamping bolt having one end thereof provided with a head for engagement with the shoulder and its other end provided with means for engagement with a saw, a removable plug threaded in the bore of the 105 casing and provided with a concaved face adapted to receive the head of the bolt, a washer interposed between the head of the bolt and the adjacent end of the sleeve, and a locking pawl swiveled on the movable handle section and adapted to engage the teeth on the sleeve when said movable handle section is rotated.

9. A device of the class described including a casing having a tubular extension and 115 provided with a transverse bore, the wall of which is formed with a stop shoulder, a saw guard having a laterally extending arm, the end of which is flattened, an internally threaded nipple forming a part of the guard and slidably mounted in the tubular extension of the casing, there being a square opening formed in said casing and communicating with the bore, a sleeve having exterior 120 threads for engagement with the threads on the nipple and provided with a circumferential row of ratchet teeth, a bolt having a head bearing against the shoulder and provided with means for engagement with a 125

saw, a plug forming a closure for one end of the bore and having a seat for the reception of the head of the bolt, and a locking pawl swiveled in the movable handle section and adapted to engage the teeth on the sleeve when said handle section is rotated, there being a transverse kerf formed in the outer face of the removable closure and

adapted to receive the flattened terminal of the guard when removing said closure.

10

In testimony whereof, I affix my signature in presence of two witnesses.
